TRAY FOR HOLDING DENTAL EQUIPMENT AND SUPPLIES

Robert M. Sronce, Lake Isabella, Calif., assignor to
Johnson Pet-Dor, Inc., d.b.a. J & S Products

Filed Mar. 21, 1975, Ser. No. 560,673

Term of patent 14 years

Int. Cl. D24—02

U.S. Cl. D24—1 R

Fig. 1.

Fig. 2.

Fig. 3.

Fig. 4.

Fig. 5.

Fig. 6.

FIG. 1 is a perspective view of a tray showing my new design;

FIG. 2 is a top plan view;

FIG. 3 is a side elevational looking toward the upper edge in FIG. 2;

FIG. 4 is an end view looking toward the left edge in FIG. 2;

FIG. 5 is an end view looking toward the right edge in FIG. 2; and

FIG. 6 is a side elevation looking toward the lower edge in FIG. 2.

The broken lines are shown for illustrative purposes only.

I claim:

The ornamental design for a tray for holding dental equipment and supplies, substantially as shown and described.
